MACHINE FOR SEASONING OR FINISHING LEATHER.

1,352,186.

Specification of Letters Patent. Patented Sept. 7, 1920.

Application filed November 13, 1917. Serial No. 201,741.

To all whom it may concern:

Be it known that I, JAMES U. FLANAGAN, a citizen of the United States, residing at Wilmington, in the county of New Castle, State of Delaware, have invented a new and useful Machine for Seasoning or Finishing Leather, of which the following is a specification.

My invention relates to a novel appliance for machines for seasoning and finishing leather, of the general type of machine disclosed in my contemporaneously pending application, Serial No. 84,033, now Patent 1,257,595, the principal object of my invention being to provide a novel device for automatically and continuously feeding seasoning liquor of an even consistency and quantity to the skins to be treated, which object I attain by conducting or discharging compressed air into the seasoning liquor below a regulated level to agitate the sediment therein to bring the seasoning liquor to an even consistency for application to the skin.

My invention further consists of novel means for confining the agitation of the liquid at a point adjacent to a fluted roller partly immersed in said liquor which is adapted to automatically conduct the liquor to a contiguous brush roll arranged in operative relation to a traveling apron upon which the skin to be treated is carried.

My invention further consists in collocating my novel liquor feeding device with a leather finishing machine comprising a continuously moving endless apron upon which the skins to be treated are carried, a brush roll onto which the liquor is fed from my novel device, said brush roll being located in proximity to the endless apron and adapted to feed and rub the liquor into the skin carried thereupon, said apron moving upwardly and downwardly over a rotatable crown shaft, adapted to stretch the skin on the grain side to permit the penetration of the seasoning liquor to the desired extent, a brush roller in close proximity to the crown shaft to rub the liquor into the skin while in a stretched condition, additional brush rolls for rubbing the liquor into the skin, and a cleansing roll for cleansing the apron preparatory to carrying a skin, which foregoing features in connection with my novel

seasoning liquor feeding device produce a machine which will satisfactorily and efficiently season or finish a skin.

For the purpose of illustrating my invention, I have shown in the accompanying drawings one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a diagrammatic view of a leather seasoning or finishing machine, showing also in side elevation my novel automatic means for supplying the seasoning liquor to the skin and agitating the same during the operation of the machine.

Fig. 2 represents a fragmentary front elevation, partly in section, of the seasoning liquor pan, fluted roll, submerged perforated air pipe and other adjuncts to insure the even consistency and supply of seasoning liquid to the fluted roll, contiguous brush roll and the skin being treated.

Fig. 3 represents a fragmentary vertical section taken on line 3—3 Fig. 1, showing the manner of collocating the pan for the seasoning liquor, the agitating device therefor, the fluted roll and coacting brush roll.

Fig. 4 represents, on an enlarged scale, a fragmentary section on the line 4—4 of Fig. 2, showing the mounting of the perforated air pipe in the liquor seasoning pan.

Similar numerals of reference indicate corresponding parts in the figures.

Referring to the drawings:

1 designates my novel construction of seasoning machine, the same comprising the framework 2 upon which are mounted the various shafts, power transmission devices, endless apron or bolster and coacting brush rolls, the manner of collocating and actuating the same being obviously capable of variation according to requirements.

3 designates my novel seasoning liquor supply device arranged in operative connection with the other instrumentalities of the machine for automatically supplying seasoning liquor of an even consistency and

quantity to the skin during the operation of seasoning or finishing the latter, the apparatus shown being one preferred form which has been found in practice to give especially satisfactory results.

5 4 designates the main shaft which is mounted in suitable bearings in the lower portion of the machine and is provided with a tight and loose pulley, the tight pulley 5
10 being secured to said main shaft, whereby power is applied thereto from any convenient source. Upon the main shaft 4 is mounted a sprocket wheel 6, around which passes the chain 7 in driving connection with the sprocket wheel 8 mounted on the shaft 9, carrying the gear 10 in mesh with the gear 11 mounted on the shaft 12.

15 Mounted on the shaft 12 is the sprocket wheel 13, which actuates the sprocket chain 20 14 in driving connection with the sprocket wheel 15 mounted on the shaft 16, which latter carries a sprocket wheel 17, which actuates the sprocket chain 18 in driving connection with the sprocket wheel 19 mounted
20 on the shaft 20.

25 21 designates a sprocket wheel on the main shaft 4 which actuates the sprocket chain 22 which is in driving connection with the sprocket wheel 23 mounted on the shaft 24 carrying the sprocket wheel 25 which actuates the sprocket chain 26 in driving connection with the sprocket wheel 27 mounted on the shaft 28.

30 29 designates a sprocket wheel mounted on 35 the main shaft 4, which actuates a sprocket chain 30 in driving connection with the sprocket wheel 31 mounted on the shaft 32, which drives the rotary or other pump 76 to be referred to.

35 40 40 33 designates a sprocket wheel mounted on the shaft 12 and around which passes the sprocket chain 34 in driving connection with the sprocket wheel 35 mounted on the shaft 36 carrying the sprocket wheel 37 around 45 which passes the sprocket chain 38 in driving connection with the sprocket wheel 39 mounted on the shaft 40.

45 50 55 41 designates a sprocket wheel mounted on the main shaft 4 and which actuates the sprocket chain 42 in driving connection with the sprocket wheel 43 mounted on the shaft 44 carrying the rear drum 45 around which passes the endless apron or bolster 46, the direction of travel of the latter being apparent from Fig. 1. Motion imparted to the bolster 46 by the drums 45 is transmitted to a drum 47 around which the bolster passes at the front end of the machine. The drum 47 is mounted on a shaft 48 carrying a gear

60 65 60 65 49 in mesh with the gear 50 mounted on the shaft 51 carrying a sprocket wheel 52 which actuates the sprocket chain 53 in driving connection with the sprocket wheel 54 mounted on the shaft 55 to which a fluted roll 67, best seen in Figs. 2 and 3, is secured

for conducting seasoning liquor from the pan 66 to the contiguous brush roll 59.

56 designates a crown shaft roller over which the apron 46 passes so that the skin 57 during its travel over the elevated portion of the apron or bolster 46 will have its grain side somewhat stretched, so as to receive the requisite amount of the seasoning liquor.

58 designates a cleaning roll which is 75 mounted upon the shaft 28 and whose function is to clean the contiguous surfaces of the apron or bolster 46. In the upper portion of the machine are located a plurality of brush rolls, such as the brush roll 59 80 mounted on the shaft 20, see Fig. 3, the brush roll 60 mounted on the shaft 16, the brush roll 61 mounted on the shaft 36 and the brush roll 62 mounted on the shaft 40, it being apparent that in the present instance 85 I have shown four of these brush rolls which are adapted to thoroughly coat the skin with the seasoning material during its passage or travel on the bolster, although it will be understood that the number of said brush rolls may be increased or diminished if desired, without departing from the spirit of my invention.

90 It will be understood that the various shafts illustrated in Fig. 1 and heretofore 95 described in connection with the drums, fluted roll, brush rolls, crown shaft, sprocket wheels, cleaning roll, pump, and their adjuncts, may be collocated and adjusted with respect to each other in any desirable manner, the form illustrated having been found to be most satisfactory and efficient in practice. The direction of movement of the drums, fluted roll, brush rolls, crown shaft, cleaning roll, pump, sprocket wheel, and their coacting shafts and gearing will be apparent from the diagrammatic view shown in Fig. 1 of the drawings, from which I have purposely omitted the housing and the specific form of the power 100 transmission devices for the sake of clearness of illustration, as these will be readily understood by those skilled in this art.

105 The mounting of the various shafts on the side frame 2-2 and the operation of the 110 above mentioned elements in respect to the apron 46 and skin 57 is preferably similar to that disclosed in my prior application, Serial No. 84,033, heretofore referred to, and represent one form of seasoning machine, to which my present invention is particularly applicable, which will now be described in detail.

115 My novel seasoning liquor feeding and agitating device 3 comprises a pan 66, which is supported by longitudinally slotted brackets 68 secured to the side frames 2. 64 designates fastening devices positioned in said slotted brackets and engaging in the vertically slotted brackets 65 secured to and 120

125 130

adjustably supporting said seasoning liquor pan 66, within which is located a revolute fluted roll 67, secured on the shaft 55 and partly submerged in the seasoning liquor contained in said pan 66, whereby said seasoning liquor is conducted to the contiguous brush roll 59, and thence to the skin 57 carried on the bolster or apron 46.

68 designates a perforated compressed air pipe submerged in the seasoning liquor contained in the pan 66, one end of said air pipe being capped as at 69, while the other end taps into the main compressed air supply pipe 70, see Fig. 2. 71 designates a control valve in the pipe 68 for controlling the supply of compressed air to the pipe 68 to be discharged through the perforations rearwardly and downwardly against the bottom of the pan 66 as seen in Fig. 4 to agitate the sediment in the liquor and insure an even consistency of the liquor during the operation of the machine.

The upper rear edge of the pan is located in close proximity to the periphery of the fluted roll 67, as will be understood from Fig. 3, so as to form a confined agitating pocket 83 in the pan between the lower portion of the fluted roll 67, rear portion of the pan 66 and the perforated pipe 68, so as to confine the agitation of the liquor in respect to the fluted roll 67 and prevent undue splashing from the pan.

72 designates several supporting blocks adapted to support the perforated air pipe 68 from the bottom of the pan 66, said pipe being so located in respect to the fluted roll 67, so as to produce the best results, and for purposes of illustration, I have shown the said pipe beneath the fluted roll and preferably on one side of the vertical axis thereof, as will be understood from Fig. 3, although it will be understood that the pan, fluted roll and air pipe may be collocated differently, if desired.

73 designates a seasoning liquor supply tank which may be conveniently located in respect to the machine for supplying seasoning liquor to the pan 66, as seen at the left of the bottom of Fig. 1. 74 designates a tap pipe leading from the main air supply pipe 70 and discharging air into the tank 73. The discharge or lower end of the pipe 74 is submerged in the liquor and the valve 75 controls the supply of compressed air through said lower end into the seasoning liquor to agitate said liquor and insure an even consistency of the seasoning liquor during the operation of the machine.

76 designates a rotary or other pump located in the pipe line 77 for raising a supply of seasoning liquor from the tank 73 to the pan 66 during the operation of the machine, said pump being operated by the shaft 32 heretofore referred to. 78 designates a valve for controlling the supply of

liquor elevated from the tank 73 to the pan 66, the position of the suction and discharge terminals of the pipe line 77 being apparent from the left of Fig. 1.

The discharge end 79 of the seasoning liquor supply pipe is formed L-shaped to insure the downward discharge of the liquor from the pipe 77 into the pan 66. 80 designates an overflow pipe, the upper end or intake 81 of which automatically regulates the depth of the liquid in the pan 66 in respect to the fluted roll 67, while the discharge end 82 communicates with and discharges into the tank 73, so that there is no waste under any conditions.

In the operation of seasoning a skin, power is applied to the main shaft 4 from which motion is transmitted to the several shafts upon or from which the various operative elements are revolved, the direction of rotation of the endless apron or bolster and the various sprocket wheels, chains, gears, and brush rolls being apparent from the arrows seen in Fig. 1. The several operations of the machine taken in their natural sequence consist in first operating the rotary pump 76 through the rotation of the shaft 32, which pumps the season liquid from the supply tank 73 through the valve controlled pipe 77 into the pan 66 adjustably supported at the front of the machine between the side frames 2. When the season liquid reaches a depth regulated by the upper terminal of the overflow pipe 80, said liquid will overflow into the intake head 81 and be returned to the tank 73, thereby automatically insuring a continuous and regulated supply of season liquid in the pan 66, irrespective of that used or carried off by the fluted roll 67 to the contiguous brush roll 59. The valve 75 of the compressed air supply line upon being opened will allow air under pressure to pass into the pipe 74 and be discharged into the tank 73 to agitate the sediment of the seasoning liquor to insure the liquid being of an even or proper consistency. The valve 71 upon being opened allows compressed air to pass into the perforated pipe 68, see Figs. 3 and 4, and be discharged rearwardly and downwardly against the bottom of the pan 66 to agitate the sediment in the season liquor therein to hold the liquor to an even consistency for application to the skins.

By the revolving of the fluted roller 67 partly immersed in the season liquid, the latter is conducted in the flutes to the contiguous brush roll 59, which when brought to the desired point of saturation is ready for treating a skin. It will therefore be readily seen that with a feeding device of this character acting automatically in conjunction with the fluted roll 67 and the brush roll 59, a continuous supply of liquor of an even consistency and quantity is con-

tinuously and automatically applied to the skins to be treated.

After the brush roll 59 is brought to the desired point of saturation, the skins to be treated are placed on the left of the upwardly inclined portion of the apron or bolster 46, seen in Fig. 1, and passed initially beneath the front or first brush roll 59 which is always kept in a proper saturated condition by the automatic feeding device 3.

It will be apparent that the front brush roll 59 which preferably revolves at about fifty revolutions per minute initially applies the seasoning liquor to the outer surface of the skin, said seasoning liquor being rubbed into the body of the skin as the latter advances by the three succeeding brush rolls 60, 61 and 62, as will be understood from the diagrammatic view in Fig. 1.

I preferably drive such brush rolls in such a manner that each successive brush roll rotates at a progressively increasing speed. It will, however, be understood that the speed or revolution of the brush rolls can be progressively increased or diminished according to the condition of the skin at the time it is ready for the seasoning operation, which applies to goat, sheep or calf skins, kips, and sides, and while the above approximate speeds of revolution are preferable, it will of course be apparent that I do not desire to be limited to any particular speed or comparative speed of rotation of the various brush rolls, it being understood that the above suggested speed of revolutions per minute for the various brush rolls are stated for the purpose of illustration of the capabilities of my machine, and that in practice, these brush cylinders may be driven at any other or desired speeds, according to requirements.

It is ordinarily desirable or preferable to rotate the brush roll 61, which is juxtaposed to and coacts with the crown shaft 56 (which may revolve as an idler or be driven) at a considerably higher rate of speed than the brush roll 59, for the reason that when the skin 57 reaches the position indicated in Fig. 1, it will be somewhat stretched, so that the contiguous brush roll 61 not only has the dual function of rubbing the seasoning liquor into the skin but in addition it also serves to propel or advance the skin over and around the apex of the angle formed by the crown shaft under the endless apron or bolster 46, said brush roll 61 serving also to exert a pull upon the skin while it is held tightly between the crown shaft and juxtaposed brush roll, so that while said skin is passing over the crown shaft, it is in a taut or stretched condition.

The outer or grain surface of the skin being straightened and stretched efficiently on said grain side, into which the seasoning is to be rubbed during its passage over the

crown shaft, the seasoning consequently penetrates the grain of the skin with great thoroughness by reason of its stretched or opened out condition and it is obvious that a much better and more uniform product is obtained and the liability of having portions of the skin remaining unseasoned or of having too great a quantity of the seasoning material at any one or more points of the skin is entirely eliminated.

It will be understood by those skilled in this art that very few skins at this stage of their finishing lie out flat or straight, since they are as a rule more or less frilled or stand up especially about the flanks and brisket of the skins. As these frilled up portions of the skin pass under the brush rolls, the tendency and difficulty heretofore has always been that the frilled portions would be folded or plaited, making three thicknesses of leather instead of one. When this happens, it will be clear that a double surface of the skin under the plait could not be acted upon by the brush roll, this being what is termed a "skip." At other times, what is termed a "pocket" would be formed in which the seasoning liquid would lie and afterward cake. The result of this caking would be that the skin would be marked wherever a cake had existed. My novel crown shaft has the function of mechanically effecting the spreading out of all plaited or frilled portions of the skin, so that by the time the latter has passed over the angle formed by the crown shaft, it lies flat and straight. It will be apparent that the formation of all frills, plaits, "skips" or season pockets are avoided by my novel construction, as the skin in its passage over the crown shaft is mechanically and automatically spread out sidewise until perfectly flat and in that condition is acted upon by the brush roll 61, it being apparent that the upper stretch of the apron 46, owing to the position of the crown shaft 56, moves in an upwardly inclined plane, as will be understood from Figs. 1 and 3, then passes around the crown shaft or roll 56 and then travels in a downwardly inclined plane, as seen in Fig. 1.

The speed of the fluted roll 67 is regulated so as to carry to the work exactly and accurately the volume of liquid required, and I desire to call especial attention to the employment of the automatic device for elevating or pumping the season liquid into the pan 66 and automatically maintaining a desired or fixed level therein, together with my novel means for effecting the desired agitation of said season liquid in both the pan 66 and the tank 73, so that said season liquid will always be applied to a skin at the proper consistency. As I am the first in the art to employ these features alone or in connection with a machine of the character hereinabove described, my claims are

to be interpreted with the corresponding scope accorded to inventions of this character.

By my invention, over six thousand calf skins can be seasoned with precision per day and forty dozen skins per hour of either goat or sheep and four hundred kips or sides per hour.

It will now be apparent that I have devised a new and useful construction of machine for seasoning or finishing leather which embodies the features of advantage enumerated as desirable in the statement of the invention and the above description, and while I have, in the present instance, shown and described preferred embodiments thereof which will give in practice satisfactory and reliable results, it is to be understood that the same are susceptible of modification in various particulars without departing from the spirit or scope of the invention or sacrificing any of its advantages.

Having thus described my invention, what I claim as new and desire to secure by Letters Patent, is:

1. The combination of a leather seasoning machine, a season liquid pan therefor, a roll rotatably mounted in said pan, a brush roll coacting with said feed roll, means for conducting compressed air into said liquid below the level thereof, and means for automatically regulating the amount of liquor in said pan.

2. The combination of a leather seasoning machine, a season liquid pan therefor, a feed roll rotatably mounted in said pan, a brush roll coacting with said feed roll, and means for conducting compressed air into said liquid below the level thereof.

3. The combination of a leather seasoning machine, a season liquid pan therefor, a fluted roll revolvably mounted in said pan, and a compressed air pipe located in said pan, and having outlet ports for discharging compressed air into the space between said roll and a wall of said pan.

4. In a leather finishing machine, a seasoning liquor containing device, means for injecting fluid under pressure into the liquor toward the bottom of said device, and means for automatically feeding said liquor to a skin.

5. In a leather finishing machine, a seasoning liquor containing device, means for injecting compressed air in the liquor contained in said device, means for automatically feeding said liquor to a skin, and means for automatically and continuously supplying liquor to said containing device.

6. In a leather finishing machine, a season liquid pan, means for agitating the liquid therein means for automatically maintaining said liquid at a constant level, and a fluted roll revolvably mounted in said pan.

7. In a leather finishing machine, a season liquid pan, means for agitating the liquid therein, a fluted roll revolvably mounted in said pan, a brush roll coacting with said fluted roll, and means for automatically keeping said liquid at a predetermined height in said pan. 70

8. In a leather finishing machine, a seasoning liquor containing device, means for injecting compressed air in the liquor contained in said device, means for automatically feeding said liquor to a skin, means for automatically and continuously supplying liquor to said containing device, and means for retaining a regulated quantity of liquor 80 therein. 75

9. In a leather finishing machine, a seasoning liquid pan, means for ejecting compressed air into said pan to agitate said seasoning liquid, means for automatically feeding said liquid to a skin, means for continuously supplying said liquid to said pan, and a revolvable fluted roll mounted in said pan. 85

10. In a leather finishing machine, a season liquid pan, means for ejecting compressed air into said pan to agitate said seasoning liquid, means for automatically feeding said liquid to a skin, means for continuously supplying said liquid to said pan, and a revolvable fluted roll mounted in said pan, 90 95 in combination with a brush roll contiguous to said fluted roll for feeding said liquor to a skin.

11. In a leather finishing machine, a skin carrying apron, means to actuate it, a brush roll for initially applying liquor to said skin, a season liquid pan, a season liquid supply tank, means for continuously supplying liquor from said tank to said pan, means for automatically regulating the amount of liquor in said pan, a fluted roll adapted to be partly immersed in said liquor, a perforated pipe submerged in said liquor and in communication with a compressed air supply agitating said liquor, and means for revolving said fluted roll to conduct season liquid to said brush roll. 100 105 110

12. In a leather finishing machine, a skin carrying apron, means to actuate it, a brush roll for initially applying liquor to said skin, a seasoning liquor containing device, a seasoning liquor supply tank, means for continuously supplying liquor from said supply tank to said liquor seasoning container, means for automatically regulating the amount of liquor in said container, a fluted roll partly immersed in said liquor, a perforated pipe submerged in said liquor and in communication with a compressed air supply for agitating said liquor, means for revolving said fluted roll to conduct seasoning liquor to said brush roll, and additional brush rolls located in proximity to said apron for rubbing said liquor into said skin. 115 120 125

13. In a leather finishing machine, a skin 130

carrying apron, means to actuate it, a brush roll for initially applying liquor to said skin, means to actuate said brush roll, a fluted roll engaging said brush roll, means 5 for driving said fluted roll and apron, a liquor containing pan, said fluted roll being partly immersed in said liquor, a submerged perforated pipe for the discharge of compressed air into said liquor, said pipe being 10 located adjacent said fluted roll, a supply tank, means for pumping the liquor from said supply tank to said pan, and an overflow pipe in said pan discharging into said supply tank for insuring the retention of a 15 given quantity of liquor in said pan.

14. In a leather finishing machine, a plurality of drums, a rotatable crown shaft located above said drums, an endless apron passing over said drums and upwardly and 20 downwardly over said crown shaft, a brush roll for initially applying a liquor to a skin to be treated, a seasoning liquor containing device, means for injecting compressed air into said liquor for agitating the same, 25 means for continuously supplying liquor to said containing device during the operation of the machine, means for retaining a regulated quantity of liquor in said containing device, a revoluble fluted roller partly im- 30 mersed in said liquor for conducting the said liquor to said brush roll, and additional brush rolls located in proximity to said apron for rubbing said liquor into said skin.

15. In a leather finishing machine, a skin 35 carrying apron, means to actuate it, means comprising a rotatable crown shaft located above and between the outer portions of said apron for producing a crown or bend in said apron, a brush roll for initially applying 40 seasoning liquor to said skin, a second brush roll in proximity to said crown, a pan for the seasoning liquor, and means for pneumatically agitating the contents of said pan.

45 16. In a leather finishing machine, a skin carrying apron, means to actuate it, means comprising a rotatable crown shaft located above and between the outer portions of said apron for producing a crown or bend in said 50 apron, a brush roll for initially applying seasoning liquor to said skin, a second brush roll in proximity to said crown, a pan for the seasoning liquor, and means for pneu-

matically agitating the contents of said pan, in combination with means for automatically supplying liquor to said pan and keeping said liquor at a predetermined height 55 therein.

17. In a leather finishing machine, a tank for containing the seasoning liquor, a supply pan for the latter, a liquor feeding device in said supply pan, a brush roll coacting with said feeding device, an overflow pipe leading from said pan to said tank, a compressed air supply pipe discharging into 60 said pan and tank for agitating the contents thereof, and means for continuously conveying 65 liquor from said tank to said pan.

18. In a leather finishing machine, a tank for containing the seasoning liquor, a supply pan for the latter, a liquor feeding device in said pan, means for automatically maintaining the height of the liquor in said 70 pan at a constant level, and means for conveying a compressed fluid into said pan below 75 the level thereof for agitating said liquor.

19. In a leather finishing machine, a tank for containing the seasoning liquor, a supply pan for the latter, a liquor feeding device 80 in said pan, means for automatically maintaining the height of the liquor in said pan at a constant level, and means for conveying a compressed fluid into said pan below the level thereof for agitating said liquor, in 85 combination with means for conveying a compressed fluid also into said tank below the level thereof for agitating the contents of said tank.

20. In a leather finishing machine, a skin 90 carrying apron, means to actuate it, means comprising a rotatable crown shaft located above and between the outer portions of said apron for producing a crown or bend in the apron, means for initially applying 95 seasoning liquor to a skin, a brush roll in proximity to said crown, a pan for the seasoning liquor, and a perforated compressed air supply pipe discharging into the liquor below the level thereof for agitating the 100 latter.

JAMES U. FLANAGAN.
